BALANCING MACHINE

Edward S. Huff, Dearborn, Mich., assignor to Ford Motor Company, Dearborn, Mich., a corporation of Delaware

Application June 17, 1932, Serial No. 617,825

13 Claims. (Cl. 73—51)

The object of my invention is to provide a device of the type known as a dynamic balancing machine whereby bodies subject to rotation may be placed in running balance. It will be understood that all solid rotating bodies may be placed in static balance and still be out of dynamic balance when rotated, the effect of such unbalance being that the centrifugal force of statically balanced portions when not axially aligned tends to rotate the axis of the body around some point thereon so that each end describes a circular path. When a body is placed in dynamic balance the axis of the body and the rotating axis coincide so that no external force need be applied to retain the body in its bearings. The advantage of such balancing when applied to internal-combustion engine crankshafts is that the unbalance which otherwise tends to oscillate the respective ends of the engine is eliminated.

There are two methods of dynamically balancing bodies, one being where weights of material equal to an overbalance are removed from the body exactly at the point of unbalance so as to place each increment or radial section of the body in static balance. The advantage of such method is that the body is not only relieved from all tendency to rotate on any axis other than its normal axis but is also relieved from all stresses set up within the body. Obviously, engine crankshafts cannot be balanced in this manner and it is not required that they be for the reason that to transmit the torsional crank loads and bending loads of the engine, the shaft must be of sufficient rigidity that it will more than resist the maximum internal stresses which might be set up due to other methods of balancing. Consequently, the machine herein described is designed to balance by another method wherein the unbalance of the shaft is not directly removed but rather wherein the effect of the unbalance on each end of the shaft is compensated for by the removal of a proportionate amount of metal from flanges on each end of the shaft. Although internal bending stresses are set up in the shaft as a result, they are not sufficient to cause any measurable deflection and, of course, do not tend to vibrate the engine in which the shaft is used.

No attempt is made to provide a machine which will directly ascertain the amount, angularity and axial position of an unbalance in the body, the sole purpose of the device being to show the effect of such unbalance on the respective ends of the shaft and to compute the amount and angularity of the metal which must be removed from the respective ends of the shaft to exactly

counteract the unbalance and therefore place the shaft in balance. One may, through subsequent calculations based upon the readings of the machine, learn the exact amount and position of the unbalance but as this information would be of no value in balancing the shaft by this method no provision is made herein for directly obtaining the figure.

In general, my machine comprises means for horizontally rotating the shaft at a predetermined constant speed while each end thereof is supported upon suitable spaced bearings. These supports are constructed to permit transverse movement relative to the shaft axis and to permit pivotal movement of the shaft around vertical centers which pass through the shaft flanges from which the metal is to be removed. In operation one of the supports is held from transverse movement and the amplitude of movement of the other end obtained. This amplitude is the resultant of the unbalance at the exact axial position of the flange. The other end is likewise balanced. The angularity is also ascertained so that it is only necessary to remove the amount of metal shown from each flange to balance the shaft. The novel feature of this construction is the means for pivoting the shaft on pivots passing through the centers of the drilling flanges so that the machine may be calibrated to read directly in inch ounces, making the use of slide rules and other like devices unnecessary.

Still a further object of my invention is to provide a machine of the class described wherein an extremely high degree of accuracy is obtained, this accuracy resulting partly from the novel method of reading the device. This method might possibly be termed a nullifying method in that the unbalance of the work causes movement in two directions of an indicator on a screen, the vertical position thereof indicating the amount of unbalance and the lateral position indicating the angularity of the unbalance. Such indicators have been used in the past but invariably the screen provided was equipped with ruled lines whereby the lateral and vertical positions of the indicator could be ascertained. My improved device is unique in that I provide micrometer adjustments whereby the positions of the indicator may be shifted back to a zero position, or that which it assumes when a perfectly balanced shaft is tested. It will be apparent that a much more accurate reading can be obtained by bringing the indicator back to a fixed cross hair on a scale and reading by a micrometer the amount of movement required to accomplish this than is

possible by directly reading the amount such indicator shows by ruling the screen upon which it is impressed.

There are other features of this machine which contribute to the accuracy and high-speed characteristics thereof, however, even though the speed obtainable with this machine is about six times as fast as any balancer known to the applicant, still it should be stressed that the increased speed of operation is not obtained at the expense of accuracy but is the result of the principle of operation and the fact that not a single operation is what has usually been called a "cut and try operation." It should be kept in mind that this machine is theoretically correct in its calculations wherein it differs from most dynamic balancers where only an approximation is obtained. Further, the machine eliminating all computation from the operator is adapted for use with unskilled labor, there being no mathematics, slide rules, calculating charts or other devices required for use therewith. It may be mentioned that the operator of the machine simply lays the shaft on open bearing supports, inserts a driving head, starts the motor, and moves two dials a portion of a revolution each to bring an indicating line to a zero point on a scale, and then reads the graduations on the two dials, one of these figures being the inches of the unbalance and the other being the angular position in degrees of this unbalance. The simplicity of this whole operation has been mentioned to show that the increased speed of production obtained with this machine is not obtained at the sacrifice of accuracy but rather results from the elimination of all calculations by the operator.

Other novel features will be described in the course of this specification, the most important of these features being the inverted pendulum type of support for the shaft, the novel electric dampener, and the tuning system whereby unbalances heretofore impossible to detect are accurately measured with a minimum of time.

With these and other objects in view my invention consists in the arrangement, construction and combination of the various parts of my improved device, as described in the specification, claimed in my claims, and illustrated in the accompanying drawings, in which:

Figure 1 shows a front elevation of a preferred form of my improved balancing machine.

Figure 2 shows a plan view of the machine shown in Figure 1.

Figure 3 shows a sectional view, taken on the line 3—3 of Figure 1.

Figure 13 is a diagrammatic view, illustrating

the optical indicating system used in this machine.

Figure 14 is a diagrammatic view, illustrating an ordinary oscillographed chart and sine wave showing the departures therefrom which are incorporated in this machine.

Figure 15 is a diagrammatic view, illustrating the mechanical amplifying system whereby transverse movements of the work supporting mechanism will be mechanically amplified prior to the optical magnification thereof.

Figure 16 is a diagrammatic view of a crank-shaft mounted upon the machine's supports, illustrating the alignment of drilling flanges with the pivotal points of the machine, and

Figure 17 is a plan view, showing an arrangement of four of my machines whereby the operating labor cost per machine may be reduced substantially in half over that required for the operation of a single machine.

Referring to the drawings, I have provided a relatively heavy box shaped cast iron frame 15 having doors 16 disposed in the front and back thereof and in each end thereof and having a top plate 17 securely fastened in place by means of bolts 18. The purpose of constructing the device in such massive proportions is so that even slight vibrations of the device will be avoided. Inasmuch as an amplification of about 1500 times is provided in this machine, the necessity of having a rigid structure for supporting the mechanism can better be appreciated.

The crankshaft 10 is rotatably mounted in a pair of supports 19 which coact with the bearings 14 thereby forming a cradle for rotation of the shaft about its axis. These supports 19 are free to vibrate in a path transverse to the axis of the crankshaft so that a universal drive is provided for rotating the crankshaft. To rotate the crankshaft a synchronous motor 20 is fixedly mounted upon the top of the base plate 17, this motor being provided with an armature 21 fixedly secured to a tubular armature shaft 22, which shaft extends out from each end of the motor. The rear extending end of the shaft 22 is secured to one member of a universal joint 23, illustrated in Figure 8, the inner member of this joint being splined at 24. It will be noted that ball bearings are used exclusively in this joint as it is imperative that the frictional resistance in the joint be a minimum and constant. The motor 20 drives through the joint 23 and rotates a splined shaft 25 which is reciprocally mounted in the splines 24 and extends back through the tubular armature shaft 22. There is, however, considerable clearance between the shaft 25 and the bore in the tube 22 so that the free end of the shaft 25 may be moved out of alignment with the axis of the motor without appreciably affecting the drive therethrough.

In order to quickly connect the crankshaft with the motor, a driving head or chuck is provided, as shown in Figure 7. The free end of the shaft 25 is fixedly secured to a diaphragm 26, the outer edge of which is clamped between a pair of discs 27 with the outer of these discs having a tubular sleeve 28 projecting therefrom which is adapted to fit over one end of the crankshaft. A key 29 is pivotally fastened in the sleeve 28 and is resiliently urged to an inward position by means of a flat spring 30, this key being adapted to fit into a keyway machined in the crankshaft whereby the timing gear is secured on the crank-shaft. Inasmuch as the keyway in the crank-shaft is always in a definite position relative to

the crankshaft throws it follows that the coupling of the sleeve 28 to the crankshaft will automatically secure the shaft in a definite angular position relative to the motor armature.

5 In operation, the crankshaft is simply laid in the two supports 19 and then the sleeve 25 is pushed down over its end and then rotated until the key snaps into place. When the balancing is completed the chuck is moved toward the right, 10 the shaft 25 sliding in the splines 24, so that the crankshaft may be lifted from the supports 19. The flexing of the diaphragm 26 compensates for the axial angularity between the crankshaft and the shaft 25, due to the reciprocation of the 15 supports. It will further be noted that the discs 27 coat with an enlarged end on the shaft 25 so that excessive angular movement of the device is prevented thereby protecting the diaphragm 26 against breakage in case the crankshaft is 20 accidentally dropped upon the chuck.

It will be noted that a shaft 31 extends transversely across the machine. A switch mechanism or controller 32 is disposed within the body of the machine so as to be connected to this shaft 25 and knobs 33 are provided on each end of the shaft 31 so that the switch may be operated from either side of the machine. The switch 32 is connected through suitable wiring and relays, whereby the motor may be started and stopped from 30 either side of the machine. The purpose of this arrangement is so that one man, stationed at the rear of the machine, may set the crankshaft in place and connect the driving chuck therewith, this man operating the knob on his side of the 35 machine to start the motor and another man, located at the front of the machine, may then take readings from certain dials on the machine and when these readings are completed he then stops the motor by means of the knob 33 on his 40 side of the machine. Certain markings are then placed on the shaft and the operator in the rear of the machine then removes same and installs another one in its place.

It is extremely important that the motor 20 be capable of operation at a constant speed and to obtain such constant speed a novel synchronous motor is provided. This motor is designed to operate exactly at 600 R. P. M., from time corrected alternating current. Further, it is desirable to provide a brake on the motor so that the crankshaft or work being balanced may be stopped in a minimum time after the readings are taken. A novel electric brake mechanism is provided which consists essentially of means for 55 reversing the current in the motor, this reversed current being controlled by the direction of rotation of the armature. Both the brake mechanism and motor construction will be described in another application as such construction does 60 not directly bear upon the machine described herein.

Referring now to the mechanism for supporting the crankshaft in position, Figures 5, 15 and 16 illustrate the construction. The frame 15 is provided with a dovetailed way 34 which extends substantially the length thereof adjacent to its rear wall and a pair of carriages 35 are reciprocally mounted in these ways so that these carriages may be positioned in any place along the way to 65 adapt the machine to various lengths of crankshafts. Each of these carriages 35 has a pair of major truss members 36 secured thereto, these truss members being resiliently secured to the front and rear faces thereof in position to extend 70 upwardly in a vertical direction. Spring steel 75

strips 37 form the connecting link between the base of the truss members and the carriage, these strips having one edge rigidly secured to the carriage while the other edge is rigidly secured to the truss member. Thus, the upper ends of these truss members are free for a limited oscillating movement around the carriage. The upper ends of each pair of truss members are likewise resiliently secured to a fulcrum plate 38 by a second pair of spring steel strips 39, the plate 38 having 10 an extension 40 formed integrally therewith which extends down between the trusses to a position adjacent to the carriage 35. From the foregoing it will be seen that the plate 38 and extension 40 may reciprocate in a transverse 15 plane through a limited movement and that the plate will always remain parallel to the base of the machine. Further, the extension 40 will likewise always be perpendicular to the base.

The extension 40 is provided with a vertical 20 bore therein in which a shaft 41 is pivotally mounted, the lower end of the shaft being secured by means of a conventional ball bearing 42 while the upper end of the shaft is rotatably mounted by means of three ball bearing rollers 25 spaced therearound. As will be noted from Figure 5, two of these ball bearing rollers are pivotally mounted in the plate 38 while the third roller is mounted upon an eccentric shaft 43 so that upon rotation of this shaft the bearing may 30 be moved radially toward or from the shaft. Thus a very close fit may be maintained between the upper end of the shaft 41 and the plate 38. This is an important feature as even a slight play 35 between the shaft and plate will cause inaccuracies in the readings of the machine.

From Figure 16 it will be seen that the upper ends of the shafts 41 are connected directly to the supports 19 and that these supports are offset in opposite directions so that the axes of the 40 shafts will be aligned with the centers of the flanges 13. The center distance between the shafts 41 is adjusted to exactly equal the distance between the flanges 13 of the crankshaft to be balanced. This one provision makes it 45 possible to provide a direct reading machine and eliminates all calculations by the operator.

Inasmuch as only one end of the shaft is measured at a time means are provided whereby the plates 38 may be selectively and rigidly held 50 against transverse movement. To accomplish this a solenoid operated clamping device is provided, as shown in Figure 10, for each of the plates 38 so that upon actuation of either solenoid the adjacent plate 38 will be held rigidly 55 with the frame of the machine. The upper portion of each extension 40 is provided with a pair of spaced blocks 44, each of which has a vertically extending V-groove therein. A pair of arms 45 are resiliently secured to the frame 15 60 by means of spring steel strips 46, the free ends of each of these arms being of V-shape so as to engage the aforementioned V-shaped grooves in the blocks 44. A solenoid 47 is disposed between the two arms 45 so that upon energizing the solenoid 47 the arms 45 are clamped toward the solenoid and thereby rigidly grip the blocks 44 65 and thus prevent transverse movement of the plate 38. Thus, when the solenoid is energized the shaft 41 and supports 19 are limited only to 70 pivotal movement on a vertical center line. However, when the solenoid is inoperative then both pivotal and transverse movement of the crankshaft is permitted.

As will be seen from Figure 15, the crankshaft 75

support is substantially an inverted pendulum and is subject to the same laws in relation to its movement. As the natural period of oscillation of a pendulum of this length is relatively slow and as it is desirable to rotate the crankshaft quite rapidly in order that small unbalances may be detected, auxiliary means are provided for increasing the natural period of vibration of the support to a point just above the frequency resulting from the rotation of the shaft. This is termed the tuning of the system herein. The crankshaft is rotated at exactly 600 R. P. M. and the natural period of vibration of the support adjusted to a point only slightly above this figure. If these two figures were made to coincide then the inertia load of the supports would be eliminated and even slight unbalances would move the supports through their full ranges. Obviously, this is undesirable, as the amplitude of the support movement is the measure of the unbalance. However, when the natural period of the pendulum is made only slightly higher or lower than the frequency of operation then only a slight resistance is offered to movement. The amount of resistance can be accurately adjusted so that only slight unbalances will cause a proportional reaction of the support. The closer the natural period of oscillation approaches the frequency of operation the more sensitive the machine becomes and the smaller its range becomes. For automobile engine crankshafts the applicant has found that a 10 inch-ounce range is sufficient giving an accuracy of less than one-tenth of an inch-ounce variation.

In order to secure this tuning, adjustable flat springs extend between the lower end of each extension 40 and the frame 15. There are four flat springs 48 required for each carriage, extending side by side in a horizontal direction. The intermediate portions of the center two springs are clamped to the opposite sides of the extension 40, while each end of these two springs is clamped by means of adjustable clamps 49 to the ends of the two outer springs. The center portions of this outer pair of springs are clamped to adjusting screws 50 which are reciprocally mounted in a pair of brackets 51, these brackets being formed integrally with and extending upwardly from each side of each carriage 35. The adjusting screws 50 are provided with suitable nuts threaded thereon whereby upon tightening these nuts the center portions of the outer pair of leaf springs may be drawn away from each other to thereby stress these springs to any desired extent. The lower end of the extension 40 being secured to the intermediate portion of the center pair of springs is free to vibrate by flexing the springs.

In order to transmit this vibration to an indicating device a beam 52 is fixedly secured to each extreme lower end of the extensions 40, these beams extending lengthwise of the machine and having bars 53 secured to each end thereof which project toward the center of the machine. The ends of each pair of bars 53 are connected by a rod 54. It will be apparent from the foregoing that regardless of the position of either of the carriages in the way 34, making contact with the rods 54 in any place along their length will transfer the vibration of the support directly to the device making contact. The purpose of providing such rods is so that adjustment of the carriages for the various lengths of crankshafts will not require the readjustment of any other part of the machine.

It is very desirable to mechanically amplify the

amplitude of vibration of the crankshaft supports because of the micrometer means for measuring this amplitude. If no mechanical amplification were provided then an extremely delicate measuring device would be required while if the movement is multiplied then only an instrument of ordinary accuracy is necessary to detect extremely small fluctuations in the supports. To thus amplify this movement a pair of minor trusses 55 are provided, the bottom portions of which are resiliently secured to a suitable bracket 56 which is rigidly secured to the base of the frame 15. Spring strips 57 form the connecting link between the lower portion of the minor trusses 55 and the brackets 56 so that the upper ends of these trusses are free for transverse oscillation. A minor fulcrum plate 58 connects each pair of upper ends of the trusses 55 through still more spring strips so that upon oscillation of either of the trusses 55 the connecting plate 58 is reciprocated transversely. An arm 59 extends downwardly from each plate 58, the lower end of which comprises what will be termed a target 60. This target is provided with a vertical slotted opening therein this slot being about $\frac{1}{8}$ of an inch long and .005 of an inch in width. A bracket 61 connects each of the lower portions of the inner minor truss members with the adjacent rod member 54, whereby transverse vibration of the rods 54 will be transmitted to the lower portion of the adjacent minor truss member and cause oscillation of same.

The foregoing mechanism constitutes an essential part of this machine, it being the mechanical amplification system whereby a slight lateral movement of the supports 19 will be converted into considerably larger transverse movement of the target 60. As shown in Figure 15, a movement of the support from one extreme position to the other, as shown by dotted lines 116, causes an equal movement of the rod 54 but this rod being connected to the minor truss 55 close to its lowermost support causes approximately eight times the transverse movement on the minor plate 58. As the target 60 is integral with the plate 58 and remains perpendicular to the base of the machine it follows that the target will likewise be moved through approximately eight times the range of the support 19. Consequently, measuring the amplitude of movement of the target 60 will be a measure of the amount or resultant of the unbalance at the end of the shaft being measured.

It has been found that some means must be provided for dampening the movement of the target when the machine is adjusted for sensitive readings, as slight vibrations in the trusses themselves tend to alter the harmonic motion theoretically described by the target. The movement of the target should be harmonic and when this movement is visually indicated and optically amplified, it should appear as a sine wave form, the degree of the wave being synchronized with the crankshaft. However, due to vibrations in the supports themselves, ripples occur on the wave front which prevent accurate reading of the position of the wave peaks. The purpose of the dampener, about to be described, is to iron or smooth out these ripples and thus allow a close reading of the sine wave curve.

Figures 4 and 5 illustrate the construction of this dampener from which it will be noted that I have provided a pair of fairly strong magnetic fields, each disposed above one of the minor plates 58. Each of these magnetic fields is produced by a core 62 having an air gap about $\frac{1}{16}$ of an

inch therein in which a copper plate 63 is disposed so as to cut the lines of force across the air gap. Suitable windings 64 are provided around the core 62 so that when these windings are energized, a strong flux density will be impressed across the air gap. The ends of the plate 63 are fastened to the plate 58 so that transverse vibration of the target mechanism vibrates the plate 63 in the air gap.

As is well known cutting the lines of force of a magnetic field is resisted in direct proportion to the speed of the member doing the cutting and that a lag will result in the indicating system due to this resistance. Of course, this resistance will result in a smaller amplitude of movement of the target but this can be compensated for by lessening the tension on the tuning springs or by graduating the device to allow for the dampening. However, the lag produced by a dampener cannot be compensated for by simply altering the graduations and can only be compensated for by any means if the lag is directly proportional to the speed of movement so as to produce a constant time element for the lag. An increased amplitude of the target results in an increase in the cutting speed of the plate, the frequency remaining constant. Of course, the increased cutting speed results in a directly proportionate increase in the movement lag but the speed increase is exactly sufficient to make the lag occupy a constant time interval over all ranges of movement. This constant time lag can only occur if the resistance of the dampener is directly proportional to the speed of the cutting plate.

The importance of this function of the dampener will be apparent when it is remembered that the lag, unlike the dampening, affects the lateral position of the wave peak and as this lateral position is used to indicate the angular location of the unbalance in the shaft, the correction for lag must be made in the angular micrometer device. As the angular micrometer must read over the same angular scale regardless of the amplitude of unbalance, it will be seen that a constant time lag is an essential requirement if the device is to measure in a theoretically correct manner.

The foregoing has been explained in detail to distinguish the advantages of this dampener over other types of dampeners not having its characteristics. For example, the resistance of a frictional dampener is constant and consequently, its time lag will be less than can be compensated for. The resistance of all fluid dampeners varies about as the square of the speed so that the time lag will be greater than can be compensated for. It is believed that only the applicant's dampener can be used and still the dampening and lag inherent in such dampeners be correctly compensated for over the full range of the instrument.

Inasmuch as the lag produced by the dampening devices must be constant and as this lag depends upon the intensity of the magnetic field, it is found desirable to provide a voltmeter 105 in the dampener circuit and also a rheostat 106 so that operation of the rheostat will vary the current in the dampener.

The device which constitutes the projection part of the system or optical lever will now be described. It may be well to mention at the outset that the applicant makes no claim to the general optical system for projecting a wave upon a transparent screen as the same has been used

for years in oscilloscopes for both visual and permanent recording of the functions of alternating currents. In such oscilloscopes the generator to be tested directly drives an eight-sided mirror and the current from the generator energizes a coil which vibrates a target. A light is transmitted through the target on to the rotating mirror, the target vibration being aligned with the axis of rotation of the mirror. Consequently, the lateral displacement of the beam is controlled by the rotation of the mirror while the vertical displacement is controlled by the vibrating target. The well known sine wave form or some variation thereof according to the generator output is thus projected upon the screen. The function of the generator for all angular positions of rotation is thus learned.

The same general device is used herein for ascertaining the movement of the target 60 and its angular relation with the crankshaft which drives the rotating mirror. There is one departure however from the conventional system and that is the positioning of a special lens in the system whereby a more concentrated light beam results.

The specific parts which make up this system comprise a centrally located source of light 67 which is housed in a suitable compartment 68 in the intermediate portion of the bracket 56. A pair of condensing lens units 69 are mounted in each side of this compartment and focus the light source upon the targets 60. It will be apparent that inasmuch as there are two targets with the light 67 placed therebetween, two condensing lenses, one in each side of the compartment 68, are required. I have also provided two telescopes 70 of about 300 power which are focused on the slot in the target 60. The light traversing the targets 60 then goes through the telescopes and is reflected upwardly at right angles by means of small prisms 71. The slots in the targets being very small in width, the lateral spread of the light therefrom will be very little. However, the length of the slot is about $\frac{1}{8}$ of an inch so that a fan shaped beam of light, as shown by dotted lines 72, is thrown from the prism 71. If desired a very small round opening could have been provided in each target 60 instead of the slot but such a small opening, approximately .005 of an inch in diameter, would allow such a small amount of light therethrough that the magnification of this light by the telescope 70 would produce a very feeble indicator reading. However, when a slot is used then a relatively large amount of light is sent through the telescope which, as has been stated, is reflected upwardly from the prism 71 in a vertical direction.

Intersecting each vertical fan shaped beam of light, I have provided a special lens 73, convex in a longitudinal plane only, the lateral section therethrough being rectangular in shape. The light from prisms 71 is thus concentrated, these concentrated beams being intersected by a second pair of prisms 74 so as to be reflected back toward the center of the machine.

Located directly above the light 67 near the top of the machine, I have provided an eight-sided mirror 75 which lies in the paths of the light beams from the prisms 74. This mirror is rotatably mounted and is driven through an eight-to-one reduction gearing directly in time with the crankshaft being balanced. It is sufficient for the present to state that upon one rotation of the crankshaft the mirror 75 revolves 75

$\frac{1}{8}$ of a revolution thereby reflecting a portion of the light beam from the prism 74 across an arcuate path. Only one side of the system is used at a time so that there is no interference from the 5 two beams. A suitable arcuate screen 76 is provided upon which the target slot is focused by the telescope. From the foregoing it will be seen that if upon rotation of the crankshaft the target 60 remains stationary, the mirror 75 will 10 simply oscillate the beam of light in a straight path from one side of the screen 76 to the other. However, if the target is vibrating in time with the rotation then this transverse movement will be amplified optically by the telescope and caused 15 to move from one end of the mirror axis to the other and back as the mirror rotates $\frac{1}{8}$ revolution. Consequently, a sine wave path will be described on the scale 16 by the light beam which would, with an ordinary harmonic motion, produce 20 a form as shown by line 77, in Figure 14. Each lateral position of the beam corresponds to a definite angular position of the crankshaft. Of course, when the target is stationary only a straight line is projected across the screen and 25 the angular position of the shaft cannot be known, however, when the shaft is out of balance the unbalance causes the target to vibrate which in turn causes the projected line to assume a wave form, the peak of which corresponds, after 30 allowing for the lag of the dampening device, to the angular position of unbalance in the shaft. Consequently, the screen may be ruled off longitudinally into degrees, as shown, and vertically into inch ounces, to ascertain the effective angular 35 position and amount of the unbalance at the flange portion of the crankshaft.

The applicant does not provide such a conventional ruled scale or employ this method of registering the amount and angularity of the 40 unbalance, the foregoing being described only to better picture the improved means or departures from the conventional whereby an accuracy many times that heretofore obtainable is invariably secured with his device. A micrometer 45 system of indicating is provided but as this apparatus is partly built into the mirror drive, this latter construction will be first described.

The means for rotatably driving the mirror 75 from the crankshaft consists essentially of stand- 50 ard worm and worm wheel gears and connecting shafts. The inner end of the motor armature shaft 22 is provided with a worm machined thereon which meshes with a worm wheel secured to one end of a shaft 78, this shaft extending into a 55 cover member 79 which is positioned over the top front portion of the machine. A second shaft 80 is operatively driven through suitable spiral gears 81 from the shaft 78, the free end of the shaft 80 extending across the axis of the mirror 60 75 at a point spaced just slightly therebelow.

Referring to Figure 3, the shaft 80 is provided with one of a pair of spiral gears 82 this gear meshing with the other spiral gear 82 which is fixedly secured to a mirror shaft 83. The shaft 65 83 is rotatably mounted in a pair of spaced ball bearings 84 so that rotation of the shaft 80 will rotate the shaft 83 through the spiral gears 82. The opposite end of the shaft 83 is tapered and an octagon shaped rotor 85 is mounted thereon. 70 A flat mirror is secured to each side of the octagon rotor 85 to form the eight-sided mirror 75. The ball bearings 84 are reciprocally mounted in a suitable sleeve 87 formed in the cover 79 and due to the spiral teeth on the gear 82 reciprocation 75 of the bearings 84, shaft 83, mirror 85 and gear

82 as a unit, will cause a relative advancement or retardation of the mirror in relation to its former position in time with the crankshaft. This retarding or advancing movement of the timing of this mirror is extremely important in connection with this device, as it forms the means whereby the angularity of the unbalanced weight is ascertained.

A relatively heavy spring 86 is provided in the sleeve 87 which resiliently urges the aforementioned mirror, bearings, shaft and gear towards the front of the machine. In order to resist this spring movement, a ball thrust bearing 88 is disposed on the front end of the shaft 83 and contacts with the inner end of a screw threaded 15 plunger 89 which is threaded into the forward face of the cover 79 in axial alignment with the shaft 83. An indicating disc 90 is rotatably mounted on a suitable bearing on the forward face of this cover 79, which disc is rotatably connected to the plunger 89 so that rotation of a knob 91 which is secured to the disc through one revolution will rotate both the disc and the plunger 89 one revolution, thereby advancing the plunger through a distance equal to the lead of the 20 screw thread thereon. The advancement of the plunger 89 moves the upper gear 82 relative to the lower gear 82 thereby causing the mirror 75 to advance or retard in its relative position. The several screw threads and angularity of the gear 25 teeth have been proportioned so that rotation of the disc 90 through one revolution will advance the mirror exactly $\frac{1}{8}$ of a turn from its former position.

Referring back to Figure 14, the purpose of 35 the aforementioned mirror advancing mechanism will be described. In this figure it will be seen that the ordinary method of reading the angularity of the wave peak is to count the number of degrees on the scale which most closely 40 bisects the peak of the wave. Inasmuch as the peak of such wave is not a sharp point, it is very difficult to judge from a scale, the size of the one illustrated, an angularity closer than about 10 degrees. On the scale shown the 45 lines are 30 degrees apart. In order to increase the accuracy obtainable with this machine, the applicant instead of reading the angular position of the wave peak, causes a relative rotation of the mirror which advances the peak of the wave 50 to a zero line. One can tell with great accuracy when the sides of a symmetrical form are symmetrically spaced about a center line so that a very accurate location of the wave peak on each side of a center line can be accomplished. The 55 periphery of the disc 90 may then be calibrated to degrees and even minutes so that when the peak of the wave form is brought back to a center line or zero position, as shown by dotted lines 109 in Figure 14, the angularity through which 60 the disc 90 has to be turned to accomplish this may be readily read off with a far greater accuracy than can be ascertained by reading the original position of the wave peak on a ruled scale.

A suitable lamp bulb 92 is installed so as to 65 direct light down against the top periphery of the disc so that a hair line placed adjacent to this periphery may be readily compared with the graduations on the disc to obtain an extremely close reading on the angularity of the unbalanced 70 force.

Referring now to Figure 5, I have provided separate means for reading the amplitude of the movement of each of the targets from micrometer graduated dials. It will be noted that each of 75

the telescopes 70 is fixedly secured in a bracket 93 which is pivotally secured at 94 on the bracket 56. This pivot is arranged to swing the telescope bodily in a substantially transverse path 5 by the oscillation of the bracket 93. A suitable beam 95 is fixedly secured to the bracket 93 and one end of this beam has a compressed spring 96 associated therewith whereby the telescope is resiliently urged at all times to a position toward 10 the rear of a machine. The other end of the beam 95 is formed having a segment shape and the lower end of a band 117 is fixedly secured to this segment said band extending upwardly where it is secured to a segment shaped bracket 97 15 which is pivotally mounted in the upper portion of the machine directly above the telescope 70. The bracket 97 is rotatably mounted in the cover 79 and due to the spring 96 and band 117 pivotal movement of the bracket 97 however slight 20 causes a similar pivotal movement of the beam 95 and telescope 70.

In order to oscillate the bracket 97 a worm wheel sector 98 is provided thereon which is in mesh with a worm 99 formed on the end of a shaft 100, the shaft being rotatably mounted in the cover member 79. A suitable disc 101 is non-rotatably secured to the outer end of the shaft 100, the periphery of the disc 101 being calibrated to read in inch ounces. The worm wheel 99 and 25 proportions of the other parts of the device are so arranged that upon one rotation of the disc 101 the telescope is moved laterally through a distance equivalent to the lateral movement of the target 60 for the maximum range of the 30 machine.

The function of this disc is that rotation thereof causes the relative position of the target and telescope to change so that the focus of the telescope, where formerly on the intermediate 40 position assumed by the slot 60 when at rest, is now moved to focus on the slot at one end of its stroke. The effect of this movement is to cause the wave peak to drop down to a zero position on the screen or that shown in Figure 14 45 by dotted lines 110. The exact amount of the movement of the disc 101 required to bring the peak of the wave down to a zero center line can be read much more accurately than the amount the wave peak is above the center line.

50 There are two reasons why such an accuracy can be effected, the first being that the peripheries of the discs 101 and 90 are approximately 20 and 30 inches, respectively, whereas the length and width of the largest screen which it is possible 55 to use is only a fraction of these dimensions. The second and most important reason, however, is that the wave peak being shifted agrees with a pair of cross hairs on the indicating scale and can be very accurately centered, whereas comparing the wave peak position with a scale leads 60 to great error, especially true where the curves are relatively flat due to slight unbalances in the shaft.

It may be mentioned that the required length 65 of the octagon mirror 75 is only about 1 inch in this machine, because only the peak of the wave is required to be projected, whereas with the conventional system a mirror length equal to the full width of the screen is required.

70 From the foregoing it will be seen that the screen used in this machine is not required to be ruled or calibrated but only need be provided with a pair of hair lines at right angles to each other. Still further, because all of the readings 75 are taken at the intersection of these two lines,

it is not only unessential but it is not desirable to include the remaining portion of the screen which is required to show a full wave. For this reason this machine has incorporated therein only that portion of the scale outlined by the 5 rectangle 102 in Figure 14. The only operation required of the operator is that he center the wave peak over the cross hairs and then read the graduations on the two dials. There are, of course, two dials 101, one for each of the telescopes, and the graduations on one of these dials may be varied to compensate for the weight of the driving shaft on one end of the crankshaft. 10

In order to protect the screen 76, a plate glass cover 103 is disposed thereover, which in order 15 to reflect exterior light from the operator's eyes is set at an angle, as shown. A shroud 104 is provided so that the operator may look down through this shroud onto the screen 76 and all exterior light will be excluded from the screen. 20

In order that each end of the machine may be alternately read, I have provided a pair of switches 107 located in the cover 79, one on each side of the machine. From Figure 12 it will be seen that upon the outer end of each of 25 the telescopes I have provided an electrically operated shutter 108 which consists essentially of a solenoid having a plunger 111 therein to which a light shutter 112 is secured. Normally, the plunger 111 is resiliently urged to position where- 30 in its shutter obstructs the passage of light from the adjacent telescope. However, when the sole- noid 108 is energized then the shutter is drawn up out of the light path and allows the light to pass from the telescope to the prism 71. 35

Due to the sensitivity of the indicating system, means are provided whereby the target may be adjusted to read exactly on the zero line when the device is at rest. This means also compensates for the effect of varying temperatures upon 40 the machine. A pair of bimetal spring strips 118 are interposed between the plates 58 and the frame 15, these strips being secured by screws 119. A pair of adjusting screws 120 are pro- 45 vided so that the tension of these spring strips may be altered. These springs adjust the position of the targets and further are designed to counteract the shifting of the target due to tem- perature changes. In this machine the target 60 must remain stationary when a true balance 50 is reached and the target image must register zero amplitude on the screen 76. Either a pos- itive or a negative reading of the image will cause an error in the balance reading. The ad- justing screw 120 tensions the spring 118 to 55 urge the target to a zero position. The spring 118 is formed of bimetal; however, if the ma- chine could be operated continuously at a con- stant temperature such a bimetal spring would not be required, because the base of the ma- 60 chine would then be at the same temperature as all of the working parts. However, during the normal operation of the machine the device is idle during the night at which time the base of the machine, together with all of the parts 65 therein, are reduced to atmospheric temperature. When the machine is started the light bulb 67, together with the solenoids 47 and coils 64, ra- diates heat which increases the temperature 70 within the machine. This causes the members 70 53 and 61 to expand more rapidly than the heavy base 15 and consequently the target 60 is forced to gradually shift from its central position. Cor- rection is made by adjusting the screws 120 which 75 change the tension of the springs 118. Of course, a

75

- simple spring strip could be substituted for each bimetal strip 118, but in such case the screws 120 would need be adjusted every minute or two until a constant temperature were reached by all 5 the parts of the device. Such a condition results only after the machine has been in operation for several hours. Consequently, the function of the strips 118 is to compensate to a large extent for the frequent adjustment of the screws 120 10 which would otherwise be required to keep the targets at their central positions. The springs deflect upon an increase in temperature to practically duplicate a continuous adjustment by the screws 120.
- 15 The operation of the switch 107 located on one side of the machine energizes the solenoid 108 on the same side and at the same time energizes the locking solenoid 47 on the opposite side of the machine, thereby pivotally holding the 20 far end of the crankshaft and allowing the adjacent end to vibrate, the opposite solenoid 108 obstructing the light from the stationary target. When it is desired to read the unbalance on the other end of the machine, the other switch 107 25 is operated which automatically reverses the connections thereby obstructing the light from the former and reversing the holding devices.
- The operation of the device is as follows:
- The machine is first adjusted for the particular 30 crankshaft or body to be balanced and the several lights turned on. The body is then laid in the supports 19 and the driving head pushed over the end and rotated until the driving key snaps into the keyway in the shaft. One of the knobs 35 33 is turned to start the motor 20. The operator of the machine then presses one of the button switches 107 thereby allowing the target image on the adjacent side to be projected upon the screen 76. The center dial 90 together with the dial 101 40 on the adjacent side of the machine is then rotated until the peak of the wave is exactly centered on the cross hairs on the screen 76. The operator then reads the angularity from the center dial and the amplitude or amount of unbalance 45 directly from the other dial. These two figures are marked on any convenient pad or even with chalk on the top of the cover 79 and without stopping the shaft the other button switch 107 is depressed which reverses the operations of the 50 clamping solenoid and light shutter switches so that the vibration of the other target is impressed upon the screen. Then the center dial and the other side dial is rotated until the peak of the wave projected is centered upon the cross hairs, 55 and then the crankshaft is stopped by means of the switch 33. The operator is provided with a gauge which he lays on the top of the machine so that he may turn the crankshaft to a predetermined angle as shown by the degree graduations 60 on the driving head and then scribes this angle across one of the flanges 13. The angle for the opposite flange is also scribed in a like manner and then the inch ounces of unbalance is marked with chalk upon the sides of the flange. The 65 crankshaft is then set up in a drill press which is provided with a feeding mechanism having an adjustable stopping device thereon, the adjustable device being calibrated to read in inch ounces so that the operator simply sets the adjustment at 70 the markings on the face of the particular flange being drilled then rotates the crankshaft so that the scribed line is aligned with the drill and starts the machine. The machine then drills out sufficient metal to automatically balance the particu- 75 lar end of the shaft. The other end of the shaft

is balanced in a like manner. The crankshaft is thus completely balanced so that it is not necessary to send the shaft back to the machine to check the accuracy of the work.

Referring to Figure 17, I have shown a preferred arrangement of machines which is particularly adapted for use on production lines where large numbers of crankshafts are to be balanced. In this arrangement I have provided four machines arranged in pairs of two each, the front 10 faces of each pair of machines facing each other and each pair being side by side. Overhead conveyor lines 113 extend along the back of each pair of machines and a man marked by circle 114 is stationed beneath each conveyor line, whose duty 15 it is to install and remove the crankshafts from the two adjacent machines. Another man is located adjacent to the other conveyor line for the same purpose. Two operators shown by circles 115 are stationed in between the two pairs of machines, these operators being required to alternately, read and mark the crankshafts on each of the adjacent machines. Experience has shown that it takes just about as long to unload a machine, place the crankshaft on the conveyor, then take an unbalanced shaft from the conveyor and install it in the machine as it does to read the machine and mark the readings on the shaft. Consequently, none of the machines are idle any portion of the time and still the maximum production can be obtained from the four machines with only four men.

Among the many advantages arising from the use of my improved device it may be well to repeat that the instrument produces a theoretically correct reading which should be distinguished from numerous other balancing machines, the readings of which are only approximations.

Still further, for the reason that the indicator readings are shifted by micrometer adjustment to a zero point, the accuracy obtained with the machine is many times greater than what could be attained if an attempt were made to read the amplitude and position of the full wave on the scale, as was heretofore the custom with this type of 40 wave indicating system.

Still further, the means whereby the whole supporting system is tuned to a frequency having its natural period of vibration slightly above the rotating frequency insures maximum amplitude of 50 movement of the device resulting from very minute unbalances in the shaft. This sensitivity is even further brought out because of the relatively light reciprocating parts employed in this machine in comparison to the heavy tables, 55 cradles and the like employed in most other types of balancing machines.

Still further, the applicant provides a novel type of electric dampener, the effect of which can be exactly compensated for in the calibration of 60 the machine.

Some changes may be made in the arrangement, construction and combination of the various parts of my improved device without departing from the spirit of my invention and it is my 65 intention to cover by my claims such changes as may reasonably be included within the scope thereof.

I claim as my invention:

1. A dynamic balancing machine comprising, 70 means for rotatably supporting the work to be balanced for movement in a path other than on its axis of rotation, the amplitude of said movement being a measure of the unbalance, indicating means, deflecting means for causing the indi- 75

- cation of said indicating means to move from a zero position by the amplitude of said movement, and micrometer means whereby said indication when deflected may be adjusted back to said zero position independently of said deflecting means, whereby the amount of deflection may be accurately ascertained by the adjustment of said micrometer.
2. A dynamic balancing machine comprising, means for rotatably supporting the work to be balanced upon a resilient support whereby unbalance in said work when rotated will cause said support to oscillate, the amplitude of oscillation being a measure of the unbalance, indicating means, deflecting means for causing the indication of said indicating means to move from a zero position by the amplitude of said oscillation, and micrometer means whereby said indication when deflected may be adjusted to said zero position, whereby the amount of deflection may be accurately ascertained by the adjustment of said micrometer.
3. A dynamic balancing machine comprising, means for rotating the work to be balanced and supporting same in such manner that unbalance therein causes reciprocating movement of the work support, an indicating means timed with said rotating means and actuated by said support to indicate the angle of unbalance by displacement of the indication of said indicating means from a zero position, and micrometer means whereby said indication when displaced may be adjusted back to said zero position independently of said timing, whereby the amount of displacement may be accurately ascertained by the position of adjustment of said micrometer.
4. A device, as claimed in claim 3, wherein said indicating means is actuated so as to cause the indication thereof to be projected upon a screen as the peak of a sine wave.
5. A dynamic balancing machine comprising, means for rotating the work to be balanced and supporting same in such manner that the unbalance therein causes reciprocation of the work support, an indicator, means for causing the indication of said indicator to move both by the reciprocation of the support and by the angular position of the work relative to said reciprocation, the amount of movement of said indication in one direction from a zero position indicating the amplitude of said reciprocation and the amount of movement of said indication in another direction from said zero position indicating said angular position, and independently operable micrometer adjusting means for shifting said indication in each of said two directions back to said zero position, whereby the amplitude of reciprocation and angular displacement of the unbalance may be accurately ascertained by the calibration of said adjusting means, respectively.
6. A dynamic balancing machine comprising, means for rotating the work to be balanced and supporting same for movement transverse to its axis of rotation caused by unbalance therein, an indicator, deflecting means actuated by the amplitude of said transverse movement causing the indication of said indicator to move in one direction from a zero line, deflecting means actuated by the angular displacement of said unbalance causing the indication of said indicator to move in a second direction from a zero line, said zero lines intersecting each other, and a pair of micrometer means for shifting said indication back in each of said directions to the intersection of said zero line positions, whereby the amount of deflection may be ascertained by the calibration of one of said micrometer means and the angularity of said unbalance ascertained by the calibration of the other of said micrometer means.
7. A dynamic balancing machine comprising, a support adapted to rotatably mount the work to be balanced, said support being constructed so that dynamic unbalance in the work causes a proportional movement of the support, a screen, means for projecting a light beam, means for moving said light beam across said screen in timed angular relation with said work, an angular scale on said screen, means for deflecting said beam laterally by and in proportion to the amplitude of movement of the work support to thereby project a sine wave upon said screen, means for measuring the amplitude and position of said wave and a dampening device connected to said support and restricting its movement comprising a plate disposed in a magnetic field so as to cut the lines of force in proportion to the movement of said support, the resistance offered to the movement of said plate being directly proportional to its speed, whereby the angular lag produced thereby can be exactly compensated for over the full range of the machine by altering the graduations on the angular scale of the machine.
8. A device, as claimed in claim 7, wherein mechanically amplifying mechanism connects the work support and the dampener plate, whereby the speed at which the plate cuts the lines of force is proportionally increased.
9. A dynamic balancing machine especially adapted for balancing crank shafts comprising, a pair of laterally spaced supports adapted to rotatably mount a pair of spaced main bearings of said crank shaft in a horizontal position, said supports each being pivotally mounted in members capable of transverse reciprocation relative to said crank shaft, means for rotating the work in said supports, and a pair of solenoid operated clamping jaws secured to said machine adjacent to each of said members, which jaws may be operatively clamped to said members so as to selectively secure said members in fixed position relative to said machine.
10. A device, as claimed in claim 7, wherein the means which connect said plate to said support transmits positive movement therebetween in both directions to thus dampen both ends of the oscillating stroke.
11. In a balancing machine, a support for rotatably mounting the work to be balanced, said support being mounted for oscillation due to unbalance in the work, a spring means adapted to control the natural frequency of oscillation of said support, indicating means oscillated by said support through connecting mechanism, and a temperature responsive means adapted to maintain said indicator in a fixed neutral position by compensating for the effect of temperature changes upon said connecting mechanism.
12. A device, as claimed in claim 11, wherein said temperature responsive means comprises a spring which resiliently urges said support away from its neutral position due to said controlling spring, the effect of said temperature responsive spring varying as the temperature of the machine varies.
13. A device, as claimed in claim 11, wherein said temperature responsive means comprises a bi-metal spring which resiliently urges said support in proportion to the temperature away from its neutral position due to said controlling spring.
